ELECTROMAGNETIC CARBON-PILE REGULATORS

Andrew Stamberger, Brockley, London, England, assignor to J. Stone & Company (Deptford) Limited, Deptford, London, England

Application October 22, 1956, Serial No. 617,559

Claims priority, application Great Britain
October 26, 1955

7 Claims. (Cl. 201—51)

This invention concerns improvements relating to totally enclosed, sealed, electromagnetic carbon-pile regulators.

In accordance with the invention one or more ballast resistors used in conjunction with a regulator are sealed into a regulator enclosure or into an enclosure in sealed communication therewith. This arrangement not only enables compactness and effective cooling and control of temperature rise to be achieved, but also ensures that all live parts are enclosed in water-tight manner and that good protection against corrosion is obtained. Furthermore, it permits of the use of convenient terminal sealing means.

The enclosure for the resistors may suitably be arranged either beside an enclosure for the magnet system of the regulator or at the end, remote from the latter enclosure, of an enclosure for the carbon pile of the regulator.

Two embodiments of the invention by way of example will now be more fully described with reference to the accompanying drawings. These embodiments are applied to electromagnetic carbon-pile regulators which are generally of the construction described in the specification of the application Serial No. 399,794, now Patent No. 2,828,395.

In the drawings:

Figure 1 is a side elevation of one embodiment of the invention as applied to such a regulator,

Figure 2 an axial section to a larger scale through a part of the regulator shown in Figure 1, and

Figure 3 a side elevation of the second embodiment.

Referring to Figures 1 and 2, the magnet system of the regulator, which is not shown but is of the kind described and illustrated in the aforesaid specification, is enclosed in a can 1 having a domed cover 2 and the pile 3 is mounted inside a ceramic tube 4 enclosed in a metal tube 5, also as described in the said specification. The end of the tube 5 at which the fixed abutment 6 for the pile 3 is located is attached to a transverse plate 7 carrying a cylindrical extension 8, with a ceramic liner 9, of larger diameter. Cooling fins 10 (Figure 1) are pressed over both the tube 5 and the extension 8, which may be slightly tapered to facilitate this. The fins are dimensioned and spaced to keep the surface-temperature rise within a predetermined limit. The ballast resistor or resistors 11 connected in the usual manner to a winding or windings of the electromagnetic regulator are wound on a ceramic tube 12 received within the liner 9. To ensure close contact between the liner 9 and resistors 11, so as to reduce the temperature rise of the latter, and also to avoid detrimental vibration effects, the liner 9 and tube 12 are tapered on the inside and outside respectively.

The end of the extension 8 remote from the can 1 and the magnet system is closed by a plate 13 which is dished inwardly for stiffness and is made of thin material having low thermal conductivity, so as to reduce the conduction of heat from the said extension to a terminal-seal

2

unit 14 supported by the said plate at its middle and to limit temperature rise of the seals in operation. The plate may also be shaped, for example circumferentially channeled as indicated at 15 in broken lines, to increase the length of the heat-conducting path to the seals. Alternatively, to reduce the temperature rise of the seals, the seal unit may be mounted at the remote end of a further cylindrical member extending outwardly from the plate 13. Interengaging formations at 16 in the plate 13 and ceramic tube 12 prevents relative rotation.

The seal unit may be a multiple hermetic seal assembly designed to mate with a weather-proof connector socket indicated in chain outline at 14' in Figure 1. One of the terminals 17 is connected to the fixed pile abutment 6. Leads, not shown, from others of the said terminals 17 to the movable pile abutment 6' and to the magnet system are carried through a duct 18, lined by a ceramic tube 19, which extends parallel to the pile 3 and communicates between the interior of the extension 8 and the interior of the magnet-enclosure can 1, its ends being connected to the transverse plate 7 and to the cover 2 respectively. An outwardly projecting thrust ring 20 fixed to the outer edge of the extension 8 is rigidly connected to the magnet system by a plurality of tie rods 21. These rods pass through seals in the cover 2 and one rod 21' or more may be adjustable in length, as described in the aforesaid specification.

After insertion of the ceramic tube 4 containing the pile 3 in the metal tube 5, the fixed pile-abutment assembly 30 is secured to the latter tube by a nut 22. The remote end of the ceramic tube 4 is located by a ceramic ring 23 from which a thin tubular extension 24 reaches to, and is sealed into, the cover 2 of the magnet-enclosure 1. The arrangements for applying pressure to the movable abutment 6' and for making electrical connection therewith may be of the kind described in the aforesaid specification.

This embodiment achieves a compact arrangement, is easy to assemble and connect up and provides a unit 40 which is symmetrical about its centre line, thereby facilitating flexible mounting of the regulator.

In the embodiment of Figure 3, a unit comprising the ballast resistor or resistors wound on a tube of insulating material and having an insulating sleeve slipped over them is mounted in a tubular enclosure 25 which is provided with cooling fins 26 on the outside. As shown, the tubular enclosure 25 may be located parallel to and close beside the magnet-enclosure can 1 to which it is rigidly secured, with a spacing block 27 between them, by means of a strap 28. The interior of the tubular enclosure 25 is connected by a U-shaped duct 29 to the outer end of the tubular, finned, pile enclosure 5, whilst a branch 30 from the said duct 29 carries the leads through the domed cover 2. Terminal seals, for example a multiple hermetic-seal assembly 31 mating with a weather-proof socket, are provided at the other end of the enclosure 25.

With the above-described arrangements, terminal seals need not be mounted on the cover 2 of the magnet enclosure 1. This is important for high-temperature conditions of operation which require the joint between the said enclosure and its cover to be silver-soldered or welded. The use of a multiple terminal seal avoids difficulties associated with the disposition of the terminal seals in other positions.

If necessary, provision may be made for cooling of both the pile and the ballast resistors by a circulating liquid coolant. Arrangements in accordance with the invention lend themselves particularly conveniently to such cooling.

I claim:

1. A totally enclosed, sealed, electromagnetic carbon-pile regulator, wherein at least one ballast resistor used in conjunction with the regulator is sealed by walls into

an enclosed space in sealed communication with, but spaced away from, a spaced enclosed by walls and containing the magnet system of the regulator.

2. A regulator as claimed in claim 1, wherein an enclosure containing at least the one ballast resistor is arranged beside the walls forming the enclosure containing the magnet system of the regulator.

3. A regulator as claimed in claim 1, wherein walls providing an enclosure containing at least the one ballast resistor are arranged at the end, remote from the enclosure containing the magnet system of the regulator, of the enclosure containing the carbon pile of the regulator.

4. A regulator as claimed in claim 1, wherein at least the one ballast resistor is wound on one and received within another hollow member of insulating material.

5. A regulator as claimed in claim 1, wherein at least the one ballast resistor is wound on one and received within another hollow member of insulating ceramic material.

6. A regulator as claimed in claim 1, wherein a wall forming part of the enclosure containing the one ballast resistor is provided with cooling fins.

7. A regulator as claimed in claim 1, wherein leads are carried between the enclosure containing the one ballast resistor and the enclosure containing the magnet system of the regulator through a duct connected to the said walls forming said enclosures.
